DAVID L. COHEN, OF PENSACOLA, FLORIDA.

Letters Patent No. 71,984, dated December 10, 1867.

IMPROVED BOAT-DETACHING TACKLE.

The Schedule referred to in these Letters Patent and making part of the same.

TO ALL WHOM IT MAY CONCERN:

Be it known that I, DAVID L. COHEN, of Pensacola, in the county of Escambia, and State of Florida, have invented a new and improved Boat-Detaching Apparatus; and I do hereby declare the following to be a full, clear, and exact description of the same, reference being had to the accompanying drawings forming part of this specification, and in which—

Figure 1 is a longitudinal vertical section through the centre of a boat provided with my apparatus.

Figure 3 is a cross-section of the block B, showing the shape of a cross-section of its dove-tail groove.

Figure 2 is a cross-section of the clamping-block C, which runs in the dove-tail groove.

Similar letters of reference indicate corresponding parts in the several figures.

The object of this invention is to furnish a device with which a ship's boat can be readily shipped or launched at sea, without danger of capsizing or fouling.

In order that others skilled in the art to which my invention appertains may be enabled to make and use the same, I will proceed to describe it in detail.

In the drawings, F is a vertical lever, pivoted at e, so as to rock "fore and aft" in the boat. A pitman, D', running to the bow, is hinged to the lever F above the pivot, and another, D, running to the stern, is hinged to the lever below the pivot. At their ends these pitmen are hinged to a block, C, the cross-section of which is shown in figs. 2 and 3, and which slides forward and backward in a dove-tail groove in the upper side of a stout block, B, fastened to the boat at the foot of the stem and stern-post. The end wall of the groove is not perpendicular, but inclined, as shown in fig. 1, for the purpose of receiving the end of a notched rod or bar, a. The notch on the bar is fitted so that a shoulder on the bar below the notch fits into the recess under the incline of the wall of the groove, so that when once in position, as shown in fig. 1, the bar a cannot be drawn vertically upward without having its lower end forced backward from the end wall of the groove. The sliding block C, when the lever F is in a vertical position, fits firmly against the back of the bar a, and confines its shoulder under the projecting wall. When the lever is in this position, therefore, the bars a a cannot be disengaged from the position in which they are thus clamped. But when the top of the lever is thrown backward both blocks C C are thrown back, and both bars a a are instantly disengaged at the same moment. The boat is hoisted up and suspended by chains or ropes, hooked into rings a' a', attached to the upper end of the bars a a. The lever F may be clamped in position by any suitable device. A simple arrangement for the purpose is shown in the drawings, consisting of a bar, G, lying alongside of the lever, with a gain in one side of it, which fits around the lever and holds it in a vertical position. The bar G may be pivoted at one end, and a pin or projection may hold the other end in the proper position. By removing the pin, or lifting the bar above the projection, and throwing it back from the lever, the latter is free, and the boat detaches itself by its own weight.

Having thus described my invention, what I claim as new, and desire to secure by Letters Patent, is—

The combination of the notched bars a a with the grooved blocks B B; the sliding-blocks C, pitmen D D' and lever F, substantially as and for the purpose described.

DAVID LOPEZ COHEN.
